UNITED STATES PATENT OFFICE.

FRANK E. CASE, OF SCHENECTADY, NEW YORK, ASSIGNOR TO GENERAL ELECTRIC COMPANY,
A CORPORATION OF NEW YORK..

INDUCTION-MOTOR CONTROL.

No. 919,537.

Specification of Letters Patent. Patented April 27, 1909.

Application filed July 8, 1908. Serial No. 442,454.

To all whom it may concern:

Be it known that I, FRANK E. CASE, a citizen of the United States, residing at Schenectady, county of Schenectady, State 5 of New York, have invented certain new and useful Improvements in Induction-Motor Control; of which the following is a specification.

My invention relates to the control of induction motors, and its object is to increase the number of accelerating connections or resistance steps obtainable with a given number of resistance sections with a comparatively slight increase in the amount of 15 controlling apparatus.

Induction motors are customarily provided with resistances in the secondary circuit which are arranged to be cut out step-by-step as the motor accelerates. If a large 20 number of resistance steps are desired, the number of resistance connections and switch contacts for controlling them becomes large.

My invention consists in the addition of impedances in the primary circuit, with 25 short-circuiting switches arranged to cut the primary impedances into and out of circuit, as the several sections of the secondary impedances are short-circuited. Thus, by a 30 comparatively small addition to the amount of control-apparatus, I am enabled to double the number of resistance steps.

My invention will best be understood by reference to the accompanying drawing, which shows diagrammatically an induction 35 motor provided with controlling means arranged in accordance with my invention.

In the drawing, A represents the primary and B the secondary of an induction motor. The secondary member is provided with 40 collector rings C. The primary winding is shown supplied with three-phase current through step-down transformers D. Impedances E are inserted in the primary leads, and these may be either inductive or non- 45 inductive.

F represents impedances in the circuit of the secondary member of the motor, which are arranged to be short-circuited step-by-step.

50 G represents electromagnetically-actuated switches for short-circuiting the primary impedances E.

H, H¹ and H² represent electromagnetically-actuated switches for short-circuiting different sections of the secondary impedances F. 55

K, K¹, K² represent electromagnetically-actuated switches for closing the primary circuit of the motor.

J represents a controlling switch for controlling the actuating windings of the electromagnetically-actuated switches. This switch J is shown diagrammatically, with its contents developed on a plane surface, and with seven operative positions in addition to 60 its off-position.

With switch J in the off-position, the primary circuit is open but the secondary circuit is complete with all the secondary impedances in circuit. When switch J is 70 moved to its first position, the electromagnetically-actuated switches or contactors K are energized, which complete the primary circuit through the impedances E. When switch J is moved to its second position, the 75 primary impedances E are short-circuited by means of contactors G. In the third position the contactors G are deenergized, and contactors H are energized. This cuts the primary impedances back into circuit and 80 short-circuits one section of each of the secondary impedances F. In moving to its fourth position, switch J maintains the contactors H energized, while reenergizing contactors G. Thus, the primary impedances 85 are again short-circuited. In its fifth position, contactors G are deenergized, while contactors H¹ are energized, thereby short-circuiting another section of the secondary impedances while cutting the primary impedances again into circuit. This cycle of 90 operations is repeated through the further positions of switch J, the primary impedances being cut into and out of circuit, as each section of the secondary impedances is short-circuited. In the last position of switch J, 95 all the impedances are short-circuited.

It will be understood that my invention permits of many modifications, as, for instance, altering the connections of the secondary resistances, so as to obtain a greater 100 number of resistance steps. Accordingly, I do not desire to limit myself to the particular connections and arrangement of parts here

shown, but aim in the appended claims to cover all modifications which are within the scope of my invention.

What I claim as new and desire to secure 5 by Letters Patent of the United States, is,—

1. In combination with an induction motor, impedances in series with the primary of the motor, impedances in series with the secondary, switch contacts for short-circuiting 10 the primary impedances, switch contacts for short-circuiting sections of the secondary impedances, and means for actuating said switch contacts to cut the primary impedances into and out of circuit as the several sections 15 of the secondary impedances are short-circuited.
2. In combination with an induction motor, means for decreasing the impedance of the primary circuit of the motor, means for 20 decreasing the secondary impedance gradually, and controlling means whereby the impedance of the primary circuit is alternately increased and decreased as the impedance of the secondary circuit is gradually decreased.
25. 3. In combination with an induction motor, impedances in series with the primary and secondary of the motor respectively,

switch contacts for short-circuiting the primary impedances, switches for short-circuiting the secondary impedances step-by-step, 30 and controlling means arranged to open and close the first named contacts alternately as the last-named contacts are successively closed.

4. In combination with an induction motor, impedances in series with the primary and secondary of the motor respectively, electromagnetically - actuated switches for short - circuiting the primary impedances, electromagnetically - actuated switches for 40 short - circuiting the secondary impedances step-by-step, and a controlling switch arranged to energize and deenergize the actuating windings of the first-named switches alternately as the actuating windings of the 45 last-named switches are successively energized.

In witness whereof, I have hereunto set my hand this 3d day of July, 1908.

FRANK E. CASE.
